UNITED STATES PATENT OFFICE.

LEON O. MCPHERSON, OF JEFFERSON TOWNSHIP, COOK COUNTY, ILLINOIS.

QUADRUPLEX TELEGRAPH.

SPECIFICATION forming part of Letters Patent No. 322,739, dated July 21, 1885.

Application filed April 23, 1885. (No model.)

To all whom it may concern:

Be it known that I, LEON O. MCPHERSON, a citizen of the United States, residing in Jefferson Township, in the county of Cook and State of Illinois, have invented certain new and useful Improvements in Multiple Telegraphy, of which the following is a specification.

My invention relates to a system of telegraph circuits and apparatus employed for the transmission of two messages in each direction over a single main line at the same time without interference. The object of the invention is to provide a simple multiple-telegraph system of this character which is rapid in its operation and free from liability of giving false signals.

The invention consists, generally, in organizing the apparatus at each station in substantially the following manner: Two batteries or battery sections are employed from which currents of either positive or negative polarity and of greater or less strength may be transmitted. A continuity-preserving key is employed for varying the strength of the currents, while a pole-changing key serves to reverse the polarity of the same, irrespective of the strength. The receiving-instruments consist of two relays, the one of which is essentially a polar relay, producing signals in response to currents of a given polarity only, while the other, which is of peculiar construction, responds to currents of a given strength without reference to their polarity. The first-named relay comprises a differentially-wound magnetizing helix or coil surrounding a pivoted core, which is capable of a slight lateral movement within the coil. The respective poles of the permanent magnet extend along the outer surface of the magnetizing helix and terminate near the free end of the pivoted core. Adjustable screws, constituting polar extensions, pass from the extremity of the permanent magnet into proximity to the core. When both sections of the helix are traversed in series by a current in a given direction, a corresponding polarity is induced in the core, and it is attracted toward one of the poles of the permanent magnet and repelled from the other. A current in the opposite direction

tends to impel the movable armature-core in the reverse direction. Suitable contact-stops are applied to the core, and the circuit of a local battery, including a sounder or other receiving-instrument, is completed and interrupted by the movements of the armature-core in any convenient manner. The second relay, which responds to currents of a given strength only, irrespective of their polarity, is constructed with a differentially-wound magnetizing helix surrounding a pivoted core-section or armature-core, and this is also capable of a slight lateral movement. It is provided with two soft-iron bars or plates, one within the coils and adjacent to the movable section, and the other exterior to the coil and upon the opposite side of the movable core-section. A tension-spring normally holds the movable section in a given position against one of its contact-points. Whenever a current traverses the two sections of the coils in series the movable section and the adjacent stationary core-section receive the same polarity at their corresponding extremities, and therefore repel each other. The plate exterior to the coils, however, receives the opposite polarity and tends therefore to attract the movable section. If the current be of sufficient strength the attraction and repulsion thus exerted will overcome the tension of the spring and the movable cross-section will be drawn from its resting contact-stop, and this result will be secured whether the current traverses the coils in one direction or the opposite. The exterior plate or bar is provided with adjustable screws of soft iron extending into proximity to the movable core-section and constituting polar extensions. These serve to afford a greater degree of attraction between the movable section of core than would otherwise be exerted across the intervening space. The circuit connections of a local battery, including a suitable sounder or other receiving-instrument, are controlled by the movements of the core-section in a manner similar to that described with reference to the first-named relay.

It frequently occurs that at the moment of a reversal of a current a slight movement of an armature-lever takes place, and such move-

ment tends to give false signals upon the receiving-instrument. For the purpose of avoiding such an occurrence a special device, which may be termed a governing relay, is employed 5 when necessary for the purpose of momentarily interrupting the connections of a local circuit in which the receiving-relay or repeating-sounder is included.

For the purpose of preventing false signals, 10 which might otherwise be occasioned by the static discharge of the main line, a condenser is employed, the plates of which are so arranged with reference to the line connections that the discharge of the condenser neutralizes 15 the current due to the discharge of the line.

In the accompanying drawings, Figure 1 is 20 a diagram showing the general organization of apparatus at one station of a quadruplex system. Fig. 2 illustrates a modification in 25 the organization, showing the application of the governing relay.

Referring to the drawings, L represents a main line leading from a distant station. Two keys, K' and K², are employed for transmitting currents to the main line from two batteries, O' and O². The strength of the battery O' is preferably one-half as great as that of O², although this ratio may be varied as found desirable. The key K' is a continuity-preserving 30 key. Its lever a' carries an insulated contact-spring, a², which normally rests against the lever. A conductor, 1, leads from the negative pole of a battery, O', to the lever a', and the spring a² is connected by a conductor, 2, with the second key, K². A contact-stop, a³, is applied to the spring a², and when the lever is depressed by the operation of the magnet a⁴ the spring is pressed away from the lever a' by reason of the stop a³. This stop is 35 connected by conductor 5 with the negative pole of the battery O².

The key K² is provided with a lever, b', having two insulated springs, b² and b³. The conductor 2 leads to the spring b². The spring b³ is connected by a conductor, 4, with the positive poles of the batteries O' and O². A conductor, 3, connects the lever b' through a switch, S, with the main line L. A working-contact, b⁴, is applied to the springs b² and b³. When 45 the key is at rest the spring b² rests against the stop b⁴ and is pressed away from the lever b'. The spring b³, however, rests in contact with the lever b'. When, therefore, the keys are 50 at rest the negative pole of the battery O' will be connected through conductor 1 and key K' to the spring b² of the key K², thence through the working-contact b⁴ with a conductor, 6, and thus with the earth, in a manner herein-after described. The positive pole of the battery O' will at the same time be connected by 55 conductor 4 with the spring b³, and thus, through the lever b' and conductor 3, with the main line L.

When the key K' alone is depressed the connections with the battery O' will be interrupted and the negative pole of the battery O² will be connected with the spring a² through

the contact a³. The positive pole of the battery will be connected with the main line in precisely the same manner as is the positive 70 pole of the battery O' when the key K' is at rest. A positive current due to the battery O² will therefore be transmitted to line.

When the key K² alone is operated the negative pole of the battery O' will be connected 75 with the spring b²; but this spring will be in contact with the lever b', so that a negative current will be sent to line from the battery O', the positive pole of this battery being connected through the spring b³, contact b⁴, and 80 conductor 6 with the earth.

When both keys are depressed the negative pole of the battery O² will be connected through the key K' with the conductor 2 in the same manner as when the key K' alone is 85 depressed, and from the conductor 2 the connections will be continued through the spring b², lever b', and conductor 3 to the main line, while the positive pole of the battery O² will be connected through the conductor 4, spring 90 b³, and contact b⁴ with the conductor 6. In this manner, when both keys or transmitters are at rest, a positive current having a given strength will be transmitted to line. When the transmitter K' alone is depressed a positive 95 current having an increased strength will be transmitted. When the transmitter K² alone is operated a negative current of less strength will be transmitted to line, and when both transmitters are operated a negative current 100 of increased strength will be transmitted. These currents are designed to operate instruments at a distant station corresponding 105 to the relays R' and R², the former of which responds to changes in strength and the latter to reversals in polarity.

The receiving-instrument R² will, for convenience, be first described. This instrument is constructed with two magnetizing-coils, respectively, included between the conductors 8 110 and 9 and 11 and 12. The conductors 8 and 11 both diverge from a common point, 7, in the conductor 6, and currents traversing the coils from this point produce equal and opposite magnetic effects upon the movable soft-iron core d' inclosed within the coils, and 115 therefore serve to neutralize each other. The core is pivoted at its lower extremity, as shown at d², while its opposite free end is laterally movable between two contact-stops, d³ 120 and d⁴. Upon the exterior of the coils of the instrument is placed a permanent magnet, d⁵, the respective north and south poles of which terminate near the upper end of the coils of the instrument. Adjustable soft-iron screws 125 d⁶ and d⁷ extend through the poles of the permanent magnet, as shown in dotted lines, into proximity to the core d', thus constituting polar extensions of said magnet. These screws are preferably located within the end plate or 130 head of the spool upon which the helix is wound, and this plate—and, in fact, the entire spool—may with advantage be of some conducting non-magnetic material—such,

for instance, as brass. One pole of a local battery, o' , is connected with the core d' , while the other pole is connected through a sounder or other receiving-instrument, T' , with the 5 stop d^4 . It is evident that the movements of the core d' will alternately complete and interrupt the circuit of the local battery. The instrument is so organized that a current in a given direction will impel the core against the 10 stop d^4 , thus operating the receiving-instrument T' , while a current in the opposite direction will impel it against the stop d^3 .

The receiving-instrument R' is also constructed with two opposing magnetizing-coils, 15 one of which is included between the conductors 9 and 10 and the other between conductors 12 and 13. These coils are so connected that a current from the conductor 6, dividing at the point 7, will tend to induce opposite 20 magnetic effects upon the core of the receiving-instrument R' , which effects will neutralize each other. Within the coils of the instrument R' there is inclosed a stationary core-section, c^2 , and a movable core-section, c' , 25 which is pivoted at c^3 . A suitable adjustable tension-spring, c^4 , tends to hold the section c' toward the section c^2 and against the stop c^5 . Upon the opposite side of the movable core-section c' , and upon the exterior of the coils 30 is placed a soft-iron plate or bar, c^6 . This is provided with two soft-iron polar extensions in the form of adjustable screws c^8 and c^9 , similar to the screws d^8 and d^9 , hereinbefore referred to. When the currents traverse both 35 coils from the conductors 9 and 10, respectively, no effect will be produced upon the cores; but when a current is caused to traverse both coils in series there will be included in the two inclosed core-sections, magnetism of 40 like polarity at the adjacent ends, and hence the section c' will be repelled from the section c^2 . The exterior section, c^6 , will receive opposite polarity at its respective ends, and will tend to attract the section c' . If the current 45 be of sufficient strength it will overcome the tension of the spring c^4 and draw the section c' away from the stop c^5 and toward the stop c^10 , overcoming the tension of the spring c^4 .

A receiving-instrument, which is preferably 50 in this instance a repeating-sounder or local relay, T' , is included in the circuit of a local battery, o' , one pole of which is connected through this instrument with the stop c^5 , while the other is connected with the movable armature-section c' . The movements of the section 55 c' , occasioned in this manner, serve to complete and interrupt the circuit of the local battery o' , and thus to operate the receiving-instrument T' .

60 The conductor 10, from one coil of the relay R' , leads to the earth at G' , while the conductor 13 leads through a suitable artificial resistance, r' , to the main line L at a point outside the switch S . When, therefore, one pole of the 65 battery O' or O^2 is connected with the main line, the opposite pole is put to the earth through the point 7 and the conductors 8, 9,

and 10. One-half of the current will reach the earth at G' , traversing one coil of each instrument R' and R^2 . The portion of current 70 which will traverse this circuit is dependent in part upon the resistance of the line, for it is this current or its equivalent which traverses the main line. The other half of the current passes from the point 7, by way of the conductors 11, 12, and 13, and resistance r' , through switch S , where it unites with the portion of the current traversing the main line; thence through the conductor 3 back to the opposite pole of the battery. This circuit constitutes 75 the artificial line, and the resistance r' must therefore be so adjusted as to approximately equal the resistance of the main line, so that the portion of the current traversing the line L and the conductors 8, 9, and 10 will be approximately equal to that traversing the conductors 11, 12, and 13, including the resistance r' . The current reaching the point 7, it will be understood, finds there two paths to the conductor 3, one through the artificial line 80 13, including the resistance r' , and the other through the earth from the point G' , and thence from the distant station through the main line. The resistance of the main line is equalized by the artificial resistance r' . 85

A condenser, E , has one of its terminals e' connected with the conductor 6, by a branch-conductor, 14, and its other terminal e^2 connected by a conductor, 15, in which is inserted a resistance, r^2 , with the earth at G' . 90

Incoming currents from the distant station traverse the conductor 3 and the batteries O' or O^2 , (whichever chances to be connected at the moment with the main line,) thence they pass through the conductor 6 to the conductor 8, 105 and reach the earth by way of one coil only of each receiving-instrument. Another, but comparatively small portion of the incoming current, will pass by the way of the conductor 13, including the resistance r' and one coil of each 110 receiving-instrument, to the point 7; thence through the remaining coil of each instrument, but this time in the same direction as the portion of the current which traverses the conductor 3, reaching the earth at G' . The 115 current thus caused to traverse the receiving-instruments will combine the magnetism in the cores of the respective receiving-instruments and will cause the same to respond to the signals of the transmitting station in a 120 manner which will be readily understood.

The switch S consists of an arm, s' , capable of being placed in contact with either of two points, S^2 or S^3 . The point s^2 is connected with the conductor 3, and the apparatus has 125 hereinbefore been described as if the arm were in contact with this point. When, however, it is desired to adjust the balance of the apparatus before commencing to operate, or to receive signals through the instruments R' and R^2 and not have the batteries in circuit, the switch-arm s' is placed in contact with the point s^3 . This point is connected by the conductor 16 with the conductor 6, so that the 130

incoming currents may reach the conductor 6 without being caused to traverse the batteries and transmitting-instruments.

It is well known that at every interruption 5 or change in the polarity of a current upon the main line a static discharge occurs which consists of a momentary current in the opposite direction. As this discharge is liable to give false signals upon the receiving-instrument, it is necessary to neutralize or destroy it, which result is effected by means of a condenser, E. It will be seen that the current transmitted upon the main line by the batteries O' and O² will be in the opposite direction 10 from that traversing the conductor 6, and therefore opposite to that which charges the condenser E. When, therefore, a discharge from the line takes place there will occur an opposite discharge from the condenser E, 15 which will tend to neutralize the static discharge in the conductor 6, and therefore no effect will be produced by the static discharge upon the instruments R' and R². The resistance r' is employed for regulating the amount 20 of charge and discharge of the condenser E.

In Fig. 2 there is shown an organization of apparatus designed especially to prevent the occurrence of false signals upon the instrument R', which might be occasioned by the 25 slight movement of the armature-core c' at the reversal of the incoming currents. This additional instrument, which may be called a "governing-relay," consists of an electromagnet, F, differentially wound, and having 30 its respective coils included in the conductors 8 and 11. It is provided with a reed-armature, f', which normally rests against a pivoted arm, f². The tension of the spring f³ presses this arm against the end of the reed 35 f'. An incoming current tends to magnetize the electro-magnet and slightly depress the reed-armature. The tension of the spring f³ keeps the arm f² in contact with the reed-armature. A reversal of the currents of the 40 lesser strength will have no perceptible effect upon the armature and its contact-arm, for the reason that the movement of the reed-armature is insufficient to throw the pivoted arm or rider f² upward against the tension of the 45 spring. The stronger current will, however, draw the armature forward such a distance that its upward movement upon a reversal 50 will throw the arm f² out of contact therewith, producing a momentary separation. A conductor leading from one pole of the local battery o' through the instrument T' is connected 55 with the arm f², while the reed-armature f' is connected with the contact-point c'. Therefore, although the reversal of the current 60 might permit the armature-core c' to touch the point c', yet the circuit of the local battery o' will not be completed because of the momentary interruption occasioned by the separation of the arm f² from the reed-armature f'.

I claim as my invention—

1. The combination, with a main line, of two

sources of electricity, two transmitting-keys, one serving to vary the strength of a current transmitted to line, and the other to reverse 70 its polarity, two receiving-instruments, the one responding to variations in strength, and the other to changes in polarity of the main-line currents, a conductor leading from one pole of the source of electricity at any time 75 having its other pole connected with the line, which conductor leads through said instruments to the earth, a second conductor leading from the first conductor through said instruments in the opposite direction to the 80 main line, and an artificial resistance included in the last-named conductor.

2. The combination, substantially as herein-before set forth, with a main line and means, substantially such as described, for transmitting currents of either of two strengths, and of either polarity upon the main line, two differentially-wound receiving-instruments, means for transmitting currents through the coils of said instruments of the polarity opposite to 90 that being transmitted upon the main line, a condenser having one plate connected with the conductor leading to the said instruments, and the other connected with the earth, whereby said condenser will receive a charge opposite to the static charge occasioned upon the main line.

3. The combination, substantially as herein-before set forth, of a main line, two batteries, means for connecting either pole of 100 either battery with said main line, two receiving-instruments included between the said batteries and the earth, a magnetizing helix applied to each receiving-instrument included between said batteries and the earth, a second 105 magnetizing helix applied to each of said receiving-instruments included between said batteries and main line, and means for determining the resistance included in the last-named circuit, substantially as described.

4. The combination, substantially as herein-before set forth, with a main line, of a receiving-instrument responding to incoming currents of a given polarity, and a second receiving-instrument responding to incoming 115 currents of a given strength, which consists of a helix, a pivoted core-section within the same, a soft-iron stationary core-section within said coil upon one side of said pivoted section, a retractile spring tending to pull said pivoted section toward said stationary section, and a soft-iron plate exterior to said coil upon the side opposite to said pivoted section.

5. In a multiple telegraph system, a receiving instrument consisting of a magnetizing coil, a pivoted core-section, a stationary core-section, means tending to hold said pivoted section toward said stationary section, a soft-iron plate exterior to said coil, and a contact 125 step for said pivoted section, substantially as described.

6. The combination, substantially as herein-before set forth, with a main line and two

differentially-wound receiving-instruments, of means for transmitting currents to said main line from one pole of a battery, and through one coil of each of said instruments in one direction to the earth from the other pole of the battery, and means for transmitting currents from the last-named battery-pole through the remaining coil of each instrument in the opposite direction to the pole connected with the line, substantially as described.

7. The combination, substantially as hereinbefore set forth, with a main line and two differentially-wound receiving-instruments, of a battery located between the main line and the receiving-instruments, means for transmitting currents from one pole of the battery to the main line and from the other in opposite directions through the coils of said instruments, a condenser bridging from the pole of the battery connected with the earth round said receiving-instrument.

8. The combination, substantially as hereinbefore set forth, with a telegraphic receiving-instrument and a local circuit, the connections of which are controlled by said receiving-instrument, of a governing relay, a circuit-controller included in the main line circuit, consisting of an armature, a pivoted

contact-arm, means for normally holding the arm against said armature, which contact-arm 30 is caused to separate from said armature under the influence of the reversal in currents of given strength, and through which armature and arm the connections of said local battery are normally completed.

9. The combination, substantially as hereinbefore set forth, with a main line and a telegraphic receiving-instrument included therein, of an electro-magnet also included in said main-line circuit, a reed armature applied to 40 said magnet, an arm resting upon said armature, a spring tending to hold said arm against said armature, and at the same time to press the latter toward its electro-magnet, a local circuit, the connections of which are normally 45 completed through said arm and armature with the contact-point and armature-lever of said first-named instrument.

In testimony whereof I have hereunto subscribed my name, this 18th day of April, A. D. 50 1885.

LEON O. MCPHERSON.
